CLAIM

The ornamental design for a user interface for a front control panel for a microprocessor, as shown and described.

DESCRIPTION

FIGS. 1-3 are front views of the first embodiment of the user interface for a front control panel for a microprocessor showing our new design wherein different screen elements are displayed in alternate positions on the central display window;

FIG. 4 is a rear view thereof;

FIG. 5 is a top view thereof and the undisclosed bottom view is a mirror image;

FIG. 6 is a right side view thereof and the undisclosed left side view is a mirror image;

FIGS. 7-9 are front views of a second embodiment thereof wherein different screen elements are displayed in alternate positions on the central display window;

FIG. 10 is a rear view thereof;

FIG. 11 is a top view thereof and the undisclosed bottom view is a mirror image; and,

FIG. 12 is a right side view thereof and the undisclosed left side view is a mirror image.
